UNITED STATES PATENT OFFICE.

CHARLES T. REDFIELD, OF GLEN HAVEN, NEW YORK.

DESIGN FOR AN ANTIRATTLER PLATE.

SPECIFICATION forming part of Design No. 28,850, dated June 14, 1898.

Application filed May 12, 1898. Serial No. 680,516. Term of patent 7 years.

To all whom it may concern:

Be it known that I, CHARLES T. REDFIELD, a citizen of the United States, residing at Glen Haven, in the county of Cayuga and State of New York, have invented and produced a new and original Design for Antirattling Plates, of which the following is a specification, reference being had to the accompanying drawings, forming part thereof.

Figure 1 is a perspective view of an antirattling plate, showing my new design; and Fig. 2 is a plan view thereof.

The leading or material feature consists of the design forming the subject of the accompanying illustration, wherein the upright wing A is arranged at an angle slightly less than a right angle to the lower or base wing B, and the wing B is tapered toward its free end. At its upper end the wing A is provided with the lateral extension C, which gives the plate an edge effect somewhat similar to the

letter Z, the extension C being much shorter than the wings A and B and the latter being curved somewhat between its ends. The upper end of the wing A is slotted at D, giving 25 such end a forked appearance.

When viewed in plan, the base section or wing B tapers gradually toward its free extremity and appears as uniting with the wing A by a widened portion at B', shoulders being produced at B², near the juncture of the wing B with the wing A.

Having described my invention, what I claim as new, and desire to secure by Letters Patent, is—

The design for an antirattling plate as herein shown and described.

CHARLES T. REDFIELD.
